Earle Seymour

UNITED STATES PATENT OFFICE.

WILLIAM A. PENFIELD, OF MERIDEN, CONNECTICUT, ASSIGNOR TO THE
BRADLEY & HUBBARD MFG. CO., OF SAME PLACE.

LAMP-BURNER.

SPECIFICATION forming part of Letters Patent No. 552,327, dated December 31, 1895.

Application filed February 4, 1895. Serial No. 537,208. (No model.)

To all whom it may concern:

Be it known that I, WILLIAM A. PENFIELD, of Meriden, in the county of New Haven and State of Connecticut, have invented a new 5 Improvement in Lamp-Burners; and I do hereby declare the following, when taken in connection with the accompanying drawings and the letters of reference marked thereon, to be a full, clear, and exact description of 10 the same, and which said drawings constitute part of this specification, and represent, in—

Figure 1, a view in side elevation of a lamp-burner constructed in accordance with my invention and shown in its normal position in 15 which the gallery is depressed; Fig. 2, a view in vertical section showing the gallery elevated as for lighting the wick and stopped by the stop-pin in position to be rotated for locking it in its elevated position by the supporting-pin; Fig. 3, a similar but less comprehensive view showing the gallery in its elevated and locked position; Fig. 4, a detached view, in side elevation, of the bearing-ring; Fig. 5, a detached broken view 20 showing the upper end of the outer wick-tube; Fig. 6, a detached plan view of the bearing-ring in the size employed for the burners of “Mammoth” lamps.

My invention relates to an improvement in 30 that class of Argand or central-draft lamp-burners in which the burner-gallery is adapted to be raised for applying a lighted taper to the wick without removing the chimney, and to be locked in its elevated position, the 35 object being to produce at a low cost of manufacture a simple, durable, and conveniently-operated burner of the type described.

With these ends in view my invention consists in a lamp-burner having certain details 40 of construction and combinations of parts, as will be hereinafter described, and pointed out in the claims.

In carrying out my invention I form an integral vertical outwardly-projecting hollow 45 rib or flute A in the bearing-ring B, which is a trifle larger in internal diameter than the external diameter of the outer wick-tube C, upon which it slides up and down and rotates, the said hollow rib or flute extending throughout 50 the width of the ring B and intersecting the upper and lower edges thereof. The said

bearing-ring B is connected with supporting-arms D, forming continuations of the spring chimney-holding fingers D' of the vertically movable and rotatable burner-gallery E, 55 which, in its depressed position, rests upon the upper edge of the burner-body F, the lower edge of which is bent inward and rigidly secured to the lower end of the outer wick-tube C. I do not limit myself, however, 60 to any particular construction of the gallery, burner-body or outer wick-tube, or to any particular means of connecting the bearing-ring B with the gallery. Of course the supporting-arms D may be varied in form, and, 65 if desired, may be made independent of the chimney-holding fingers D'. The bearing-ring B, it will be understood, supports and steadies the gallery as it is moved up and down. When the gallery is in its elevated 70 position, as shown in Fig. 2, it is apparent that a lighted taper may be inserted between its lower edge and the upper edge of the burner-body for lighting the wick. For supporting the gallery in its elevated position I 75 form a short locating-notch a in the lower edge of the ring B in such a position that the inner end of the notch, which is arranged horizontally, intersects the lower end of the hollow outwardly-projecting rib A. This 80 notch receives a supporting-pin or projection c, located in the outer wick-tube C at such a distance below the upper end thereof that when the ring is raised on the tube to the height required for the convenient application under the gallery of a lighted taper to the wick the said pin will be in line with the inner end of the notch a, the said end intersecting, as before described, the extreme lower end of the hollow rib A. If now the gallery and 90 its bearing-ring are slightly rotated from right to left, the pin c will emerge from the lower end of the rib into the notch, the upper wall of which will engage with the pin, as shown in Fig. 3, in such a manner that the pin will then 95 support the gallery in its elevated position. Then to restore the gallery to its normal position it is rotated for a distance represented by the length of the notch from left to right, whereby the pin will be brought into line with 100 the lower end of the hollow rib or flute, which will clear the pin and permit the gallery to de-

scend to its normal position, in which it is supported by the upper edge of the burner-body F. As herein shown, the outer wick-tube C is provided with two additional pins c' and 5 c², located below the pin c and in line therewith and coacting with the flute or rib to prevent the gallery from being rotated in its depressed position when the upper edge of the bearing-ring lies below the pin c, which does 10 not, therefore, assist in restraining the rotation of the gallery. If desired, the bearing-ring might be made broad enough so that in the depressed position of the gallery the pin c would be available for holding it against 15 rotation; but the use of the pins c' c² answers the same purpose and is cheaper. If desired, the pins c' and c² might be replaced by a rib applied to or struck out from the tube C. If desired, also, the pin c might be replaced by 20 a projection struck out from the tube C.

For preventing the gallery from being lifted too high and accidentally removed from the outer wick-tube, which might involve the dropping of the lamp in case the same was 25 carelessly lifted by grasping the gallery portion of the burner, I form a short locating-notch a' in the upper edge of the ring B on the opposite side of the hollow rib or flute A from the notch a aforesaid, the inner edge of 30 the notch a' intersecting the extreme upper end of the said rib or flute in the same manner that the inner edge of the notch a intersects the flute. This notch a' coacts with a 35 stop-pin c³, mounted in the outer wick-tube at a point above the supporting-pin c and laterally separated therefrom by a distance corresponding to the distance through which the gallery may be rotated. In the normal adjustment of the burner—that is to say, when 40 the gallery is in its depressed position—the stop-pin c³ is in line with the lower edge or wall of the notch a', while at the same time the supporting-pin c and also the pins c' and c² are located in line with the hollow rib or 45 flute A. The stop-pin c and the pins c' and c² will not now interfere with the lifting of the gallery; but when the gallery has reached a predetermined elevation the stop-pin c³ will be engaged with the lower edge of the notch 50 a', as shown in Fig. 2, and the gallery firmly held, so that it can neither be lifted higher nor removed from the lamp without rotating it. If it is desired to lock the gallery in this 55 position, it is rotated from left to right, whereby the stop-pin c³ is caused to enter the upper end of the rib A, and the supporting-pin c brought into line with the upper wall of the notch a, as shown in Fig. 3. In 60 this position of the gallery it is supported against depression by its weight and the weight of the chimney; but if it is lifted it will be removed from the outer wick-tube, inasmuch as the stop-pin c³ is now in line with the hollow rib A. But perhaps the most im- 65 portant function of the stop-pin is to check the lifting of the gallery and bearing-ring in the position for their rotation to lock them in

their elevated position, for the use of the stop-pin relieves the operator of gaging the lifting of the gallery or burner preparatory to 70 locking it in its elevated position, and makes the operation of the burner very convenient.

I have described the bearing-ring as being provided with only one set flute or rib, and the outer wick-tube as being provided with 75 only one set of pins; but by preference I employ two corresponding ribs and sets of pins. As shown in Fig. 6 the ring is provided with two ribs, which are located opposite each other. 80

I would have it understood that I do not limit myself to the exact construction shown and described, but hold myself at liberty to make such changes and alterations as fairly fall within the spirit and scope of my invention. 85

Having fully described my invention, what I claim as new, and desire to secure by Letters Patent, is—

1. In a central-draft lamp-burner, the combination with the gallery, outer wick-tube and burner-body thereof, of a bearing-ring connected with and depending from the gallery, and adapted to ride up and down and be rotated upon the outer wick-tube, and constructed with an integral outwardly projecting hollow rib or flute intersecting its upper and lower edges, and with a short locating notch formed in and parallel with the lower edge of the ring and at its inner edge intersecting the lower end of the rib or flute; and an outward projection located in the tube and coacting with the said notch and rib or flute, substantially as described. 90

2. In a central-draft lamp-burner of the Argand type, the combination with the gallery, outer wick-tube and burner thereof, of a bearing-ring depending from and connected with the gallery, and adapted to ride up and down and be rotated upon the outer wick-tube, and constructed with a vertically arranged, integral, hollow rib or flute intersecting its upper and lower edges, and further constructed with two short locating notches located in and parallel with its upper and 100 lower edges, on opposite sides of the rib or flute respectively and at their inner ends intersecting the same; a supporting projection located in the outer wick-tube and co-operating with the lower notch, and a stop projection also located in the outer wick-tube but in a different vertical plane from the said supporting projection and co-operating with the upper notch, substantially as described. 110

3. In a central-draft lamp-burner, the combination with the gallery, outer wick-tube and burner-body, of a bearing-ring depending from the gallery and adapted to ride up and down and be rotated upon the outer wick-tube, and constructed with a vertically arranged integral, hollow rib or flute intersecting its upper and lower edges, and with a short locating notch formed in and parallel with its lower edge and intersecting at its in- 120

ner end the lower end of the rib or flute; and
two or more stop projections located in the
same vertical line on the outer wick-tube the
upper stop projection coacting with the said
5 rib and notch and the lower stop projection
or projections coacting with the rib, substan-
tially as described.

In testimony whereof I have signed this
specification in the presence of two subscrib-
ing witnesses.

WILLIAM A. PENFIELD.
